HOSE NOZZLE

Charles H. Koeppel, North Woodbury, Conn., assignor to Scovill Manufacturing Company, Waterbury, Conn., a corporation of Connecticut

Application April 23, 1956, Serial No. 41,157

Term of patent 7 years

(Cl. D91—1)

Fig. 1

Fig. 2

Fig. 3

Fig. 1 is a side elevation of a hose nozzle embodying my new design;

Fig. 2 is a front end view of the same; and

Fig. 3 is a rear end view of the same.

I claim:

The ornamental design for a hose nozzle, substantially as shown.
